AIR POWERED ROTOR LAUNCHER

William J. Burgess, Nohly, Mont.

Filed Mar. 3, 1959, Ser. No. 796,891

1 Claim. (Cl. 46—82)

This invention relates to toys and more particularly to an air powered toy.

It is an object of the present invention to provide an air powered rotor launcher that can be easily operated by any child or adult, that will send a heavier than air rotor into flight in response to initial high speed rotation thereof by pressurized air supplied from the mouth of the operator.

Another object of the present invention is to provide an air powered rotor launcher of the above type which contemplates the vertical ascent of an air powered rotor from the launcher in response to initial rotation thereof by air pressure responsive turbine wheel vanes forming a part of the launcher.

Other objects of the invention are to provide an air powered rotor launcher bearing the above objects in mind which is of simple construction, has a minimum number of parts, is inexpensive to manufacture and efficient in operation.

For other objects and for a better understanding of the invention, reference may be had to the following detailed description taken in conjunction with the accompanying drawing, in which:

Figure 1 is a side elevational view, with parts broken away, of a rotor launcher made in accordance with one form of the present invention in operative use;

Figure 2 is a top plan view of the assembly shown in Figure 1, with parts broken away;

Figure 3 is a side elevational view of a slightly modified form of construction; and

Figure 4 is a top plan view of the assembly shown in Figure 3.

Referring now more in detail to the drawing, and more particularly to Figures 1 and 2 thereof, an air powered rotor launcher toy 10 made in accordance with the present invention is shown to include an elongated tube 12 having a longitudinal bore 13 extending throughout the entire length thereof that communicates with the interior of a segmental circular guard or cylindrical type housing 14 which defines a space 16 within which a turbine wheel 18 is rotatably supported. Said turbine wheel includes a spindle 15 supported upon the bottom circular wall of said housing and journalled in a bearing type circular aperture in the upper circular wall of said housing. This turbine wheel has a plurality of vanes 20 integrally secured with said spindle which extend radially outwardly at an acute angle relative to the periphery of the turbine wheel. Thus, air passing through the longitudinal bore 13 and supplied from the mouth of the operator, impinges against the blades 20 to effect rotation of the turbine wheel 18 within the guard 14. The upper end of the spindle 15 includes an extension 22 that extends through the bearing type aperture in the upper wall of the guard 14 and terminates in a non-circular stud portion 28 that is slidably

2

received within a similarly shaped central opening in the hub 25 of a rotor.

The rotor further includes an annular rim 24, a hub portion with a non-circular vertical bore therein, and four integral radially extending blades 26 which lie in planes which define acute angles with the general plane of the rotor. Thus, as soon as the rotor attains a sufficient speed, while being driven by the turbine wheel 18, to apply sufficient lift to the blades 26, the rotor will rise vertically, as shown in Figure 1, out of engagement with the stud 28 of the spindle 22, and will assume free flight for a substantial distance.

In Figures 3 and 4 of the drawing, a slightly modified form of construction 30 is shown wherein the toy includes an elongated tubular member 32 having a pressurized air outlet at one end, adjacent to which a wire frame 34 is secured, such as by a plurality of convolutions 36 at one end of the wire frame. The opposite end of the wire frame includes a spindle portion 38 upon which a turbine wheel 40 having a plurality of vanes 42, is rotatably supported. This turbine wheel includes a stud 48 and an integral non-circular extension 50 that is slidably received within a similarly shaped opening in the hub 51 of the rotor. This rotor also includes an annular ring 44 and a plurality of radially extending blades 46 that define acute angles with the general plane of the rotor. Thus, air supplied by the mouth of the operator passes through the tube 32 and impinges upon the vanes 42 of the turbine wheel 40, thus effecting rotation of the rotor therewith until the rotor attains sufficient speed to impart lift to the blades 46 that will raise it into free flight from the turbine wheel stud 50.

It will now be recognized that all of the operating parts of the present invention can be conveniently constructed from plastic, paper, or metal products, except that in the embodiment illustrated in Figures 3 and 4, the frame 34 is preferably constructed from metallic wire.

While various changes may be made in the detail construction, it shall be understood that such changes shall be within the spirit and scope of the present invention as defined by the appended claims.

What I claim as new and desire to protect by Letters Patent of the United States is:

In a toy of the character described, the combination with a vertical cylindrical housing having an annular side wall, a non-perforated horizontal circular bottom wall, and a horizontal, circular top wall, said top wall embodying a circular bearing type aperture centrally located therein but otherwise imperforated, an elongated tube connected to said housing in eccentric relation with said side wall thereof and communicating with the interior of said housing, a turbine wheel horizontally and rotatably arranged within said housing, said turbine wheel having a vertical cylindrical spindle with a plurality of integral vanes, said vanes extending radially outwardly from said spindle and at an acute angle relative to the periphery of the turbine wheel, said spindle extending vertically above and below said vanes, the lower portion of said spindle extending downwardly from said turbine wheel being relatively short and having its lower free end in rotatable bearing contact with the non-perforated upper surface of the closed lower wall of said housing, the portion of said spindle extending upwardly from said turbine wheel extending through said circular bearing type aperture in said top wall and terminating in a non-circular stud portion, a rotor having an annular rim, and an integral hub portion with four integral, radially extending blades, said four blades being rigidly supported at

the outer end thereof by said annular rim and arranged in planes which define acute angles with the general plane of the rotor which is assembled horizontally relative to said housing, said hub portion of said rotor having a vertical non-circular opening therethrough and detachably mounted upon said non-circular stud portion of said spindle for rotation therewith in response to the introduction of pressurized air into said tube for effecting rotation of said turbine wheel.
